MANIFOLDING ASSEMBLY FOR MAILING

Otto Blitz, Oakland, Calif., assignor to Pacific
Manifolding Book Company, Inc., Emeryville,
Calif., a corporation of Delaware

Application January 13, 1936, Serial No. 58,813

11 Claims. (Cl. 282—25)

This invention relates to improvements in manifolding assemblies, and more particularly to such assemblies employing record and transfer sheets and adapted to constitute mailing envelopes.

It is one of the objects of the invention to provide an improved manifolding assembly of the character described whereby inscriptions written on the outer surface of a record leaf will be transferred to interior record surfaces within a closed envelope, and also to transfer only selected data such as address to the outer surface of the envelope.

It is a further object of the invention to provide an improved manifolding assembly including a closed envelope wherein carbonized or transfer sheets are retained in interleaved relation for transferring inscriptions to the inner surfaces, but may be readily removed from the envelope after performing their transfer function, and before the inscribed envelope is deposited in the mail.

Still another object of the invention is to provide a manifolding assembly of the character mentioned including an envelope having an improved and convenient arrangement for transferring the inscriptions to the inner record surfaces of the envelope and also providing for quick and easy opening of the envelope by an improved arrangement of weakened severance lines.

Another object is to provide an improved manifolding mailing envelope having an improved arrangement of record leaves and transfer surfaces, and especially well adapted for making up invoices or similar statements and transmitting them through the mails, saving time in making the statements and avoiding errors.

A further object is to provide a manifolding assembly of the class mentioned having an improved manner of attaching the record leaves together in the assembly so as to avoid placing stresses upon the sheets constituting the assembly and thereby avoiding wrinkling, puckering and similar irregularities in the sheets such as tend to impair the legibility of the inscriptions and interfere with the proper transferring of said inscriptions. Other objects and advantages of the invention will be in part pointed out in the following detailed description of certain illustrative but preferred embodiments of the invention and will be in part obvious in connection therewith.

The invention accordingly comprises an article of manufacture possessing the features, properties, and the relation of elements which will be

exemplified in the article hereinafter described and the scope of the application of which will be indicated in the claims.

For a more complete and comprehensive disclosure of the nature, objects and advantages of the invention, reference is had to the following detailed description and to the accompanying drawings, in which:

Fig. 1 is a perspective, partially diagrammatic view of a manifolding assembly embodying the invention;

Fig. 2 is a view similar to Fig. 1, but showing the outer detachable record leaf turned backwardly to reveal the address surface of the envelope;

Fig. 3 is an enlarged, diagrammatic edge view of the assembly of Fig. 1;

Fig. 4 is another view similar to Fig. 1 with the carbon sheets removed;

Fig. 5 is a perspective view showing one of the attaching marginal portions of the envelope removed;

Fig. 6 is a view similar to Fig. 1 showing a modified embodiment of the invention; and

Fig. 7 is an enlarged diagrammatic edge view of the assembly shown in Fig. 6.

Referring to the drawings for a detailed description of the illustrative embodiments of the invention there shown, and first to the embodiment of Figs. 1 to 5 inclusive, a unitary manifolding assembly is shown which is flexible and pliable throughout its extent so as to be readily adapted for being written upon in typewriting and similar machines, or to be manually inscribed. This record or manifolding assembly includes a top or overlying record sheet 10, a bottom record sheet 11, and it also may include an intermediate record sheet 12 in cases where an extra copy of the inscribed matter is required. These three record sheets are attached together in the assembly along opposite marginal portions thereof by means of any convenient attaching means, lines of paste 13 and 14 being employed for this purpose as shown in the drawings. It will be understood that these adhesive attachments are shown in the drawings diagrammatically and are greatly exaggerated in thickness in order to portray more clearly and fully the embodied structure.

Each of the record sheets 10, 11 and 12 is provided with a record surface facing upwardly and each record surface is preferably provided with blank forms for receiving the inscribed data and also may have certain explanatory printed matter thereon. The upper surface of the outer

record sheet 10 has a space 15 for receiving the mailing address, a space 16 for the postage stamp, and a space 17 for the return address. The inner record surfaces may be appropriately ruled and have appropriate descriptive matter printed thereon for the accommodation of the entry of any desired inscriptions as illustrated, for example, in Fig. 5.

Overlying the record sheets 10, 11 and 12 is an additional record or fly leaf 18 detachably attached to the other leaves of the assembly. As shown, this overlying fly leaf is preferably attached at only one of its edges and is preferably provided with a weakening line of severance 19 adjacent to its attached edge to facilitate severance from the assembly. This fly leaf is also ruled and bears descriptive printed matter similarly to the record sheets 11 and 12, the blank forms and printed matter being in registering relation in all of the different sheets of the assembly, so that inscriptions made in any of the spaces provided therefor on the fly leaf 18 will be transferred to the corresponding spaces of the inner record surfaces by transfer means as more fully described below. The fly leaf 18 also has an address space 20, and directly beneath the address space the fly leaf is provided on its opposite or rear surface with a carbonized area 21 so as to transfer the address inscribed on the outer surface of the fly leaf to the address space 15 of the record sheet 10. This carbonized surface 21 is of restricted extent so that only the inscriptions written in the address area 20 will be transferred to the upper surface of the record sheet 10; data inscribed at parts of the surface of the fly leaf outside of the address space will not be transferred to the record surface of the sheet 10, but will be transferred to the inner record surfaces of the other record sheets in a manner later described.

It is preferred in some instances to make the record sheets 10, 11 and 18 form a single integral strip of paper having folds at the opposite edges of the assembly so as to bring the sheets in relatively superposed overlapping relation with each other, as shown. Also the record sheets 10 and 11 are provided with weakened severance lines 22 extending along the marginal portions thereof inside of the attachment 13. These weakened severance lines may be made in any well known manner, such as by providing perforations in these sheets, or by scoring or cutting partly through the paper. Similarly, the record sheets 11 and 12 are provided with weakened severance lines 22 extending along and just inside of the attachment 14, while the outside or address record sheet 10 may not be correspondingly provided with a weakened severance line at this edge portion of the assembly. By means of the severance lines arranged as described, the record leaves may be quickly and easily detached from each other and from the assembly by tearing the paper along the weakened lines.

It is preferred, as shown, that the record leaves of the assembly be attached together only at their opposite edges, thus leaving the angularly disposed or end edges free from attachment with each other, but one or both ends may be closed by detachable or severable means if desired. The construction and attachment of the record leaves described provides an envelope or pocket closed at its opposite edges and having at least one open edge or end portion. This arrangement provides for the reception within the envelope or pocket of transfer material shown in this illustra-

tive embodiment as transfer leaves or sheets 23 which are positioned in transfer relation with the record receiving surfaces of the record leaves 10 and 12. These transfer sheets are preferably co-extensive with the record receiving surfaces of the record leaves and are provided with transfer material only on their under surfaces. Inasmuch as the transfer sheets are ordinarily used for only a single transfer inscription, the coating of transfer material is preferably very light and the paper is very thin and inexpensive in manufacturing costs.

These transfer sheets are preferably not positively attached to other parts of the assembly but are retained in their operative position within the envelope by the frictional contact of the record sheets lying closely in contact with the carbon sheets. It will be understood that the record and transfer sheets are diagrammatically depicted in the drawings, being shown as separated from each other for the purpose of portraying the structure more clearly. In practice all of the sheets lie in close contact with each other so that the complete assembly is very thin and flexible so as to be received readily by the writing machines. In order to provide a convenient means for removing the carbon sheets from the envelope when the transfer inscriptions have been completed, a selective group formation is provided whereby the transfer sheets can readily be grasped to the exclusion of the record sheets and thus withdrawn from the assembly. In the embodiment shown, this selective grip formation includes notches 24 formed in the marginal portions of the record sheets 10, 11 and 12 through which adjacent marginal portions of the transfer sheets are exposed. This offset relation of the adjacent edges of the record and transfer sheets exposes a grip area at the edge portions of the transfer sheets by means of which the latter may be readily removed from the assembly.

As shown in Figs. 1, 2 and 3, it will be noticed that the intermediate or inner record sheet 12 is attached in the assembly only at the marginal binding stub 14, its opposite end being unattached in the binding stub 13. Also the end edges of the record sheet 12 are unattached. While this attachment of the record sheet 12 is sufficient to retain it positively in position, the sheet is permitted to freely adjust itself with reference to the other sheets, thus tending to avoid stresses in these sheets resulting in wrinkles, bulges and similar irregularities tending to interfere with the entry of the inscriptions and with the clear and legible transfer thereof to the record surfaces by the transfer material. Inscriptions written on the outer or fly leaf of the assembly are transferred to the record surfaces of the sheets 11 and 12 by means of the carbon or transfer sheets 23 and the address inscription is transferred to the address space of the envelope by means of the restricted area of transfer material 21. When the inscriptions are completed, the transfer sheets may be removed as described, and the fly leaf severed along its weakened line 19 and retained by the issuing office. The envelope thus completed may then be transmitted through the mails. The receiving office may then open the envelope by severing the binding margin 13 along the adjacent weakened lines 22, whereupon the inner record surfaces may be inspected. The inscribed record leaves 11 and 12 can then be severed from the binding stub 14 by tearing along the adjacent weakened lines 22 whereupon the

address sheet 10 together with its attached binding stub 14 may be discarded.

In the embodiment of the invention shown in Figs. 6 and 7, the construction is similar to that above described, but the assembly of this form includes only the upper or address record sheet 10a and the lower record sheet 11a, the intermediate record sheet being omitted. Also but a single transfer sheet 23a is employed. In this embodiment, it is preferred that the upper or fly record leaf 18a and the record leaves 10a and 11a be formed of separate and independent sheets of paper attached together at the binding stubs 13a and 14a formed in a manner similar to the attachments above described. The fly leaf 18a is provided with a carbonized area 21a of restricted extent for transferring the address to the address area of the envelope in a manner similar to that above described. Except as herein noted, the structure and arrangement of this embodiment are similar to the embodiment above described and will be understood without a further detailed description. The operation in use is also similar to that of the prior embodiment.

In cases where it is desired to have more than one of the outside fly leaves corresponding to the fly leaves 18 or 18a, this leaf may be extended sufficiently and folded along a line parallel to the longitudinal edges of the assembly, so as to provide two or more of such leaves arranged in superposed manifolding relation with each other. When this leaf is thus folded, the fold line may be perforated or otherwise weakened to provide for easy detachment of the leaves from each other. Also, the outer fly leaf or leaves may have a carbon coating on their rear surfaces to provide for transfer inscription to the underlying fly leaf or a separate transfer leaf inserted between the fly leaves may be provided for this purpose. The carbon or transfer leaves of the assembly as above mentioned are preferably of the one time type and of light, thin material, but they are diagrammatically shown in the drawings by means of relatively heavy lines in order to distinguish them from the record leaves. The record leaves may be of any desired quality and weight of paper, but they will ordinarily be of somewhat heavier stock than the transfer leaves.

Since certain changes may be made in the above article and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is.

1. A manifolding assembly including, in combination, record sheets having attachment with each other at opposite marginal portions thereof and being free from each other at another marginal portion so as to form an open pocket, a transfer sheet loosely received within said pocket in transfer relation with the record sheets, a selective grip formation at the opening of said pocket whereby the transfer sheet may be selectively gripped to the exclusion of the record sheets and thus removed from its transfer position in the assembly, and an outer record leaf attached to the assembly and lying in contact with the outer surface of one of said record sheets, said outer record leaf having a transfer surface of restricted area positioned to transfer the address inscription to said outer surface, and also having record receiving areas outside of

said restricted transfer area and in registry with said transfer sheet, and with similar record receiving areas within said pocket with which said transfer sheet is in transfer contact.

2. A manifolding assembly including, in combination, record sheets having attachment with each other at opposite marginal portions thereof and being free from each other at another marginal portion so as to form an open pocket, a transfer sheet loosely received within said pocket in transfer relation with the record sheets, and a selective grip formation at the opening of said pocket whereby the transfer sheet may be selectively gripped to the exclusion of the record sheets and thus removed from its transfer position in the assembly, said assembly including an inner record sheet within the pocket and attached only at one of its marginal portions, the attachment of said inner sheet being at one of said opposite marginal attachments. 20

3. A manifolding assembly including, in combination, record sheets having attachment with each other at opposite marginal portions thereof and being free from each other at another marginal portion so as to form an open pocket, 25 a transfer sheet loosely received within said pocket in transfer relation with the record sheets, a selective grip formation at the opening of said pocket whereby the transfer sheet may be selectively gripped to the exclusion of the record 30 sheets and thus removed from its transfer position in the assembly, said assembly including an inner record sheet within the pocket and attached only at one of its marginal portions, the attachment of said inner sheet being at one of 35 said opposite marginal attachments, and an outer record leaf attached to the assembly and lying in contact with the outer surface of one of said record sheets, said outer record leaf having a transfer surface of restricted area positioned to transfer the address inscription to said outer surface, and also having record receiving areas outside of said restricted transfer area and in registry with said transfer sheet, and with similar record receiving areas within 40 said pocket with which said transfer sheet is in transfer contact. 45

4. A manifolding assembly including, in combination, record sheets having attachment with each other at opposite marginal parts thereof to form a mailing envelope, a transfer sheet within said envelope in transfer relation with the record sheets, and a record leaf detachably attached to the envelope to overlap the address surface thereof and having a transfer surface of restricted area in transfer relation with the address area of the envelope to transfer address inscriptions thereto, said overlapping record leaf having inscription receiving space apart from said restricted transfer area and in registry with 55 said transfer sheet whereby inscriptions made on said leaf will be transferred to a record surface within the envelope. 60

5. A manifolding assembly including, in combination, record sheets having attachment with each other at opposite marginal parts thereof to form a mailing envelope, said envelope being open at one marginal portion thereof, a transfer sheet within said envelope in transfer relation with the record sheets, a record leaf detachably attached to the envelope to overlap the address surface thereof and having a transfer surface of restricted area in transfer relation with the address area of the envelope to transfer address inscriptions thereto, said overlapping record leaf 70

75

having inscription-receiving space apart from said restricted transfer area and in registry with said transfer sheet whereby inscriptions made on said leaf will be transferred to a record surface within the envelope, and a selective grip formation at said marginal portion of the envelope whereby the transfer sheet may be removed.

6. A manifolding assembly including, in combination, record sheets having attachment with each other at opposite marginal parts thereof to form a mailing envelope, a transfer sheet within said envelope in transfer relation with the record sheets, and a record leaf detachably attached to the envelope to overlap the address surface thereof, and having a transfer surface of restricted area in transfer relation with the address area of the envelope to transfer address inscriptions thereto, said overlapping record leaf having inscription receiving space apart from said restricted transfer area and in registry with said transfer sheet whereby inscriptions made on said leaf will be transferred to a record surface within the envelope, said record sheets having weakened severance lines lying inwardly of the attachment thereof whereby said sheets may be detached from each other by severance along said weakened lines.

7. A manifolding assembly including, in combination, record sheets having attachment with each other at opposite marginal parts thereof to form a mailing envelope, a transfer sheet within said envelope in transfer relation with the record sheets, a record leaf detachably attached to the envelope to overlap the address surface thereof and having a transfer surface of restricted area in transfer relation with the address area of the envelope to transfer address inscriptions thereto, said overlapping record leaf having inscription receiving space apart from said restricted transfer area and in registry with said transfer sheet whereby inscriptions made on said leaf will be transferred to a record surface within the envelope, said record sheets having weakened severance lines lying inwardly of the attachment thereof, whereby said sheets may be detached from each other by severance along said weakened lines, said envelope having an open edge portion for removal of the transfer sheet, and a selective grip formation at said open edge portion whereby the transfer sheet may be withdrawn from the envelope.

8. A manifolding assembly including, in combination, record sheets having attachment with each other at opposite marginal parts thereof to form a mailing envelope, a transfer sheet within said envelope in transfer relation therein, a record leaf detachably attached to the envelope to overlap the address surface thereof and having a transfer surface of restricted area in transfer relation with the address area of the envelope to transfer address inscriptions thereto, said overlapping record leaf having inscription receiving space apart from said restricted transfer area and in registry with said transfer sheet whereby inscriptions made on said leaf will be transferred to a record surface within the envelope, and a record sheet within the envelope in transfer relation with said transfer sheet and attached at only one edge portion thereof to the assembly.

9. A manifolding assembly including, in combination, record sheets having attachment with each other at opposite marginal parts thereof to

form a mailing envelope, a transfer sheet within said envelope in transfer relation therein, a record leaf detachably attached to the envelope to overlap the address surface thereof, and having a transfer surface of restricted area in transfer relation with the address area of the envelope to transfer address inscriptions thereto, said overlapping record leaf having inscription receiving space apart from said restricted transfer area and in registry with said transfer sheet whereby inscriptions made on said leaf will be transferred to a record surface within the envelope, said record sheets having weakened severance lines lying inwardly of the attachment thereof whereby said sheets may be detached from each other by severance along said weakened lines, and a record sheet within the envelope in transfer relation with said transfer sheet and attached at only one edge portion thereof to the assembly and having a weakened severance line whereby it may be severed from its attachment with the assembly.

10. A manifolding assembly including, in combination, record sheets having attachment with each other at opposite marginal parts thereof to form a mailing envelope, one or more transfer sheets within said envelope in transfer relation with the record sheets, a record leaf detachably attached to the envelope to overlap the address surface thereof, and having a transfer surface of restricted area in transfer relation with the address area of the envelope to transfer address inscriptions thereto, said overlapping record leaf having inscription receiving space apart from said restricted transfer area and in registry with one of said transfer sheets whereby inscriptions made on said leaf will be transferred to a record surface within the envelope, said record sheets having weakened severance lines lying inwardly of the attachment thereof whereby said sheets may be detached from each other by severance along said weakened lines, a record sheet within the envelope in transfer relation with one of said transfer sheets and attached to the assembly and having a weakened severance line whereby it may be severed from its attachment with the assembly, said envelope having an open edge portion for removal of one or more of the transfer sheets, and a selective grip formation at said open edge portion whereby the transfer sheet may be withdrawn from the envelope.

11. A manifolding assembly including, in combination, record sheets having attachment with each other at opposite marginal parts thereof to form a mailing envelope, one or more transfer sheets within said envelope in transfer relation with the record sheets, said record sheets having weakened severance lines lying inwardly of the attachment thereof whereby said sheets may be detached from each other by severance along said weakened lines, and a record sheet within the envelope in transfer relation with one of said transfer sheets and attached at only one edge portion thereof to the assembly so as to permit it to adjust itself and to avoid wrinkling and bulging thereof, said inner record sheet having a weakened severance line whereby it may be severed from the assembly, said envelope having an open edge portion for removal of the transfer sheet and a selective grip formation at said open edge portion whereby the transfer sheet may be withdrawn from the envelope.

OTTO BLITZ.
